(57) **CLAIM**

The ornamental design for an electric spin brush, as shown and described.

DESCRIPTION

FIG. 1 is a front perspective view of the electric spin brush, showing the first embodiment;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the electric spin brush, showing a second embodiment;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view of the first embodiment, shown in condition of use;

FIG. 18 is a perspective view of the second embodiment, shown in condition of use;

FIG. 19 is an enlarged detail view taken from line 19 in FIG. 1; and,

FIG. 20 is an enlarged detail view taken from line 20 in FIG. 1.

The broken lines in the drawings illustrate the portions of the electric spin brush, which form no part of the claimed design.

The dash-dot-dash broken lines encircling the enlarged views are for annotative purposes only and form no part of the claim thereof.

1 Claim, 20 Drawing Sheets
